Primary Examiner — Mark Goodwin(74) *Attorney, Agent, or Firm* — Dentons US LLP(57) **CLAIM**

The ornamental design for an irrigation implement, as shown and described.

DESCRIPTION

FIG. 1 is a perspective view of an irrigation implement showing our new design;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

The broken lines in the drawings are indicative of environmental structure or boundaries that form no part of the design to be patented.
